(57) CLAIM

The ornamental design for a handheld fabric sweeper with icon, as shown and described.

DESCRIPTION

FIG. 1 is a rear, top, right side perspective view of an embodiment of a handheld fabric sweeper with icon showing my new design;

FIG. 2 is a rear elevation view thereof; and,

FIG. 3 is a top plan view thereof.

Wherein the broken lines form no part of the claimed design.

1 Claim, 3 Drawing Sheets

FIG. 1

FIG. 3
